CLAIM

(21) Appl. No.: 29/323,790

The ornamental design for a paper bag with a transparent vertical window for salad ingredients, as shown and described.

(22) Filed: Aug. 29, 2008

DESCRIPTION

(51) LOC (9) Cl. 09-05

FIG. 1 is a perspective view of a paper bag with a transparent vertical window for salad ingredients showing our new design;

(52) U.S. Cl. D9/703

FIG. 2 is a front elevational view thereof;

(58) Field of Classification Search D9/703-707,

FIG. 3 is a rear elevational view thereof; and,

D9/709, 713, 720, 643-648, 652, 414-416;
426/106; 222/92, 107; 383/61.1, 78, 81,
383/84, 108, 112, 115; 229/87.06, 87.07

FIG. 4 depicts the paper bag with a transparent vertical window for salad ingredients, with the new, original and ornamental design in a display.

See application file for complete search history.

The written matter: “Thoroughly Washed,” “No Preservatives,” “Best if used by:,” the “Net Wt.” information, “Tender Whole Leaf Baby Lettuces” and “Spring Mix” as depicted in the drawing figures, form no part of the claimed design. The stylized “Fresh Express,” and the stylized leaf pattern are trademarks of Fresh Express, Inc.

(56) References Cited

The broken line showing of a shelf is included for the purpose of illustrating the bag in display and forms no part of the claimed design.
